UNITED STATES PATENT OFFICE.

PHILIP STRROUP, OF CLEVELAND, OHIO.

INSTANTANEOUS ELECTRIC-SOCKET ATTACHMENT.

1,213,035.

Specification of Letters Patent. Patented Jan. 16, 1917.

Application filed November 22, 1915. Serial No. 62,871.

To all whom it may concern:

Be it known that I, PHILIP STRROUP, a citizen of the United States of America, residing at Cleveland, in the county of Cuyahoga and State of Ohio, have invented new and useful Improvements in Instantaneous Electric-Socket Attachments, of which the following is a specification.

This invention relates to electric plugs and has for its primary object to provide a device of this character having the inherent properties of being readily attached and detached from a socket in a very short interval of time.

An object of the invention is to provide a simple construction and at the same time insure a good electrical contact.

Another object of the invention is the simple manner of arranging the elements so as to prevent short circuits or flash overs between the parts connected at the opposite conductors of the circuit.

Other objects of the invention will appear hereinafter in the novel combination of elements as pointed out in the appended claim.

In the drawings—Figure 1 is a vertical section through an electric socket showing my invention applied thereto, the invention being shown in side elevation. Fig. 2 is an enlarged vertical section through the plug. Fig. 3 is a side elevation looking at right angles to Fig. 2. Fig. 4 is a perspective view of the blocks of which the plug is composed. Figs. 5, 6 and 7 are cross sectional views through the plug. Fig. 8 is a vertical section through a modified form of my invention. Fig. 9 is a horizontal section therethrough.

Referring to the drawings, the numerals 1 and 2 designate the side supporting blocks made of insulating material, one of which being provided with the laterally extending portion 3 having passages 4 through which pass bolts 5 that have threaded engagement with the opposite side blocks. The other side block in this particular instance, block 1, is provided with lugs 6 provided with threaded passages 7 for a purpose hereininafter described. Rigidly formed with the side block member 1 is a bushing 8 and the latter if found advantageous can be detachably held between the blocks 1 and 2 in any suitable manner such as by bolts. This bushing 8 is provided with a bore 9 having its axis extending vertically. In the pre-

ferred form of my invention, this bore 9 receives a bolt 10 having its end 11 resting upon the upper end of the bushing and a threaded end 12 receiving the usual nut 13 between which is frictionally held an end of the current wire 14. Passing through the lugs 6 that is to say, through the passages 7, are bolts 15 that detachably engage the adjacent lower ends of a pair of opposite leaf springs 16 and 17, each having its upper end integrally formed with or detachably connected to a contact 18. These contacts 18 are of arcuate shape in cross section so as to conform to the curvature of the threaded bore of the socket 19 to increase the amount of contact between the contact members and threaded bore of the socket member. I show the contact members corrugated so that the ridge thereof will fit between the threads of the socket 19. For moving the contact toward the bushing for readily allowing the plug to be attached to the socket, I rigidly secure to the leaf springs push buttons 20 of insulating material that slide in the spaces formed between the blocks 1 and 2. From this arrangement it will be seen that when pressure is exerted upon the buttons, the leaf springs will be forced toward each other for carrying the contact members toward the bushing. After the device is forced a suitable distance within the socket, pressure is relieved from the button with the result that the resiliency of the leaf springs forces the contact members into tight engagement with the threaded bore of the socket and at the same time prevents movement of the end portion of the bolt 10 away from the contact portion 21 of the socket. The remaining current wire of the circuit is rigidly secured to one of the leaf springs, but I wish it to be understood that the same can be readily attached to both leaf springs and depends entirely upon the amount of current to be fed to the branch circuit.

In the modified form of my invention I have shown a more simple construction which can be manufactured at much less expense. In this form of my invention I have provided an elongated insulated bushing 22 having an enlarged lower end portion 23. The bushing 22 is provided with a longitudinally extending bore 24 through which passes one of the current wires 25 that has its extremity extended beyond the upper end of the bushing and flattened so as to rest thereupon. Thus it will be seen that I have

provided an enlarged portion for engaging the contact button of the socket. Passing around the enlarged end portion 23 of the bushing is a middle portion of a substantially U-shaped spring 26 that terminates in laterally extending end portions 27 that form contacts that engage the threaded bore of the socket. This U-shaped spring is rigidly secured to the bushing by means of bolts, one of which is firmly connected with the remaining current wire 26.

Obviously, various changes could be made in certain parts of the apparatus by one skilled in the art without departing from the spirit and scope of the invention and for this reason I desire not to be limited to the precise arrangement and construction of parts as disclosed.

What I claim and desire to have protected by Letters Patent of the United States is:—

In a device of the character described, a two part block bolted together, one of said parts being formed with a pair of spaced lugs for spacing the parts, leaf springs each having one end secured to a lug and its other end formed into a contact and a button secured to each spring and working between said parts.

In testimony whereof I affix my signature in presence of two witnesses.

PHILIP STROUP.
